UNITED STATES PATENT OFFICE.

HERMAN SNATER, OF ACKLEY, IOWA.

WASHING MACHINE.

Application filed March 2, 1926. Serial No. 91,701.

My invention relates to improvements in washing machines, and one of my improvements consists in providing for the tub means for segregating and evacuating sediment during the process of washing articles therein while separating the articles from the accumulated sediment. Another improvement is in supplying a combination of rocking dollies adapted to thoroughly shift and agitate articles in the tub at both its upper and lower levels.

With the foregoing and other objects in view which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

My invention is illustrated by the annexed drawings, in which Fig. 1 is a vertical axial section of my washing machine with parts broken away, Fig. 2 is a top plan thereof with the hinged cover removed and parts broken away, and Fig. 3 is a detail section on a larger scale, showing one of the cups and its port of the lower dolly-carrying separating disk.

The open top tub 1 is preferably constructed of metal such as aluminum and is provided with a hinged cover 2. The body of the tub is of one piece with a large central bottom circular aperture within which is fitted a bottom closure 6, which, as with other parts of the machine are preferably castings. The bottom closure 6 is marginally supported upon an annular supporting shelf and removably secured thereto by bolts 36. From its side walls the bottom of the tub is slightly coned downwardly toward the periphery of the closure 6 and its upper face is preferably shaped with inclined radiating ribs 39 between which are the radiating troughs 30 to conduct sediment inwardly. At the inner ends of these troughs 30 is an annular low ridge 31, and this ridge is apertured radially with inwardly inclined small holes or passages 32 whose inner ends deliver upon the upper face of the peripheral margin of the closure 6. The radial troughs 30 are relatively shallow and each delivers into the outer end of one of the passages 32. The closure 6 is downwardly dished to provide a sump 33 to receive col-

lected sediment and communicates with a drainage pipe having a valve-controlled terminal faucet.

The outer bottom part 29 is supported on the legs 3. Means are provided for vertical adjustments of the legs, comprising casters whose shanks 4 are mounted in sockets in the lower ends of the legs, both the shanks and the sockets being supplied with aligned apertures for insertion of bolts 5 when a desired adjustment is effected.

The closure casting 6 is formed with a centrally raised portion which is axially apertured at 8 to receive the rock-shaft 9, and the latter may be rocked to and fro throughout a desired distance by driving mechanism not shown as this is not claimed in my invention.

This raised central part of the bottom casting 6 is carried upwardly centrally through the tub 1 as an axially hollowed conically tapering body 7 which at its upper end becomes cylindrical and is interiorly fitted with a bronze bearing sleeve 10 for the shaft 9. The upper end of the shaft 9 is threaded at 18 to take a terminal nut 16 secured thereto also by means of a countersunk setscrew 17. Upon the angular nut 16 an enlarged head block 14 is removably fitted at 15. From the block 14 depends a reduced cylindrical part 12 mounted loosely about the upper part of said fixed part 7. Another and outer sleeve part 19 is mounted around the depending part 12 and secured thereto by means of rivets 13. The sleeve 19 is a casting which is conically enlarged downwardly at 22 to and integral with a bottom horizontal disk 26. This disk 26 overlies the bottom closure 6 and projects also over a portion of the tub bottom 29 nearly to the annular ridge 31. On the parts 19—22 are integral radial dollies 20—21. The upper face of the bottom disk 26 has integral radial ribs or dollies 23 whose inner ends are integral with the sleeve part 22.

As shown in Figs. 1 and 2, the disk 26 has apertures as shown in Fig. 3 at 28 which effect communication between the interior of the tub above and below the disk, and said apertures have raised side opening hoods 27, the hoods being alternated in opening in opposite directions, each hood being positioned medially between a pair of the ribbed dollies 23. In advance of the upper mouth of each hood 27 is a radial ridge or baffle

34 to arrest water dashed against it so as to deflect the water to drive over the hood instead of through the aperture 28, whereby water may move quietly through the aperture 28 without interference.

Within the sump space 33 below said disk 26 sediment may collect, principally by way of the passages 32. In order to prevent violent stirring up of the sediment in the bottom of the sump, I have mounted a division plate 34 just below the delivery lower mouths of the apertures 28 of said disk, which thus divides the sump interior into vertically separated parts, the lower thus kept undisturbed by eddies which may be formed in the upper space under the disk 26 because of the rocking and reversals of direction of the latter. This division plate 34 is circular with a serrated peripheral edge 38 and has numerous small apertures 37 through which sediment bearing water may quietly pass. The serrations 38 are circumferentially curved upwardly nearly to the bottom of the disk 26 to thus practically close the space under said disk, but the plate 34 in its marginal part underlies the parts 38 to nearly close the sump space below while permitting passage therebetween of sediment from the holes 32. The depending hollow rock body 22 has a sleeve part 24 depending below the disk 26 and rockably mounted upon a bronze bearing member 25 fitted upon the central raised portion of the closure 6.

35 In the operation the dollies are rocked reversely about 225 degrees and as both upper and lower sets of radial dollies at 21 and 23 respectively are provided, spaced vertically, articles in the tub are agitated both above and below with clearance between said sets of dollies allowing room for sufficient water circulation therebetween and thus through the foldings and convolutions of the articles, but the latter may be driven centrifugally outwardly by the dollies without entanglement or tearing, as the dollies are horizontal and do not project downwardly into the clothes as in many other machines.

50 This centrifugal and loosening action on the clothes in the tub loosens and discharges dirt outwardly toward the side wall of the tub to subside and as sediment flow down the radial bottom troughs 30 to the holes 32 and under the stationary disk 34 into the sump.

60 The disk 34 divides the water under the rocking plate 26 so that the water in the sump 33 remains still and unaffected by any eddies or swirling of the water above the disk 34 caused by the rocking and reversing of the disk 26.

The cups or hoods 27-28 on the disk 26 act when the disk rocks back and forth, by picking up the water in advancing for-

wardly and pushing it around whereby the water head under the disk is lessened enough as to create a circulation of water by way of the troughs 30 and holes 32 to the sump 33 and through the serrations 38, under the disk 34 leaving sediment in the sump, then the water thus cleaned rises through the disk holes 37 and through the hooded apertures 28 in the rocking disk 26 to complete the circulation.

75 Having described my invention, what I claim as new, and desire to secure by Letters Patent, is:

1. In a washing machine, a tub having a detachable dished bottom sump of less diameter than that of said tub, controllable drainage means for said sump in communication therewith, the outer bottom region of the tub being sloped toward the sump and having an annular apertured ridge concentric therewith, an apertured divisional device removably mounted over the sump only, and dollies rockably mounted in the tub above said divisional device.

80 2. In a washing machine, a tub having a detachable dished bottom sump of less diameter than that of said tub, controllable drainage means for said sump, the outer bottom region of the tub being sloped downwardly and having its upper face shaped 85 with radial troughs delivering to the sump, an apertured divisional device removably mounted over the sump, and rockable devices mounted in the tub above said divisional device for carrying and agitating articles to be washed.

90 3. In a washing machine, a tub having a detachable dished bottom central sump of less diameter than that of said tub, controllable drainage means for said sump, the outer bottom region of the tub being sloped downwardly toward the sump and having its upper face shaped with radial troughs, said bottom region having a raised annular ridge concentric with the sump and having apertures leading from said troughs inclinedly into said sump, an apertured cover for said sump, and agitating devices mounted rockably within the tub above said cover.

100 4. In a washing machine, an open top tub having a bottom central opening of less diameter than that of said tub, a dished sump secured in said opening detachably and having drainage means, said sump having a central axial bearing opening, a rock-shaft mounted rockably in said bearing opening, vertically separated dollies supported on said rock-shaft within the tub to have an unimpeded space between them, and a divisional device removably supported in said tub above the sump and below said dollies.

110 5. In a washing machine, an open tub having a bottom sump, a removable apertured cover for said sump, the tub having delivery passages leading into the sump,

- and a rockable agitating and clothes carrier device mounted removably in the tub above said cover, the carrier part being immediately above the said cover, of discoidal 5 shape and apertured, and the agitating part of the device comprising radial dollies above said carrier part spaced vertically to provide an open central space in the tub.
6. In a washing machine, a tub having a 10 dished bottom sump, an apertured and marginally serrated divisional device supported removably over said sump and having an extension margin below the serrated part, the bottom of the tub without said sump 15 having conduits leading into the sump below the said extension margin, a rockable disk supported in the tub above said divisional device and having apertures with hoods covering their upper ends, the hoods being 20 arranged in pairs alternated to open oppositely in the opposite directions of rocking of the disk, and agitating devices mounted upon said disk to project thereabove and separating said hoods from each other.
7. In a washing machine, a rockable agitating device mounted removably, a tub containing said device, said device comprising a bottom horizontal discoidal part spaced from the bottom of the tub, vertically spaced agitating radial dollies mounted 25 upon said discoidal part, said discoidal part having hooded apertures whose hoods are arranged alternately to open oppositely, and said discoidal part having raised baffle ridges positioned in advance of the mouths 30 of said hoods to divert liquid over the same when said mouths are advancing into the liquid in their forward movements.

In testimony whereof I affix my signature.
HERMAN SNATER.
